By E. S. Wheeler, Attorney.

Attorney.

UNITED STATES PATENT OFFICE.

JOHN WALLACE PAGE, OF ADRIAN, MICHIGAN.

GATE FOR WIRE FENCING.

1,132,792.

Specification of Letters Patent.

Patented Mar. 23, 1915.

Application filed June 3, 1912. Serial No. 701,193.

To all whom it may concern:

Be it known that I, JOHN WALLACE PAGE, a citizen of the United States, residing at Adrian, in the county of Lenawee, State of Michigan, have invented certain new and useful Improvements in Gates for Wire Fencing; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to a gate for wire fencing, and consists in the construction and arrangement of parts hereinafter more fully set forth and pointed out particularly in the claims.

The object of the invention is to provide a gate for flexible wire fencing of the staple (so called) and woven wire types, wherein provision is made for opening a section of said fencing to allow the passage of a team or stock therethrough, the arrangement being such as to enable the hinged or swinging portion of the fencing which comprises the gate to be supported in a vertical position when opened, notwithstanding its light and flexible character, and for securely fastening the hinged section when closed, so as to hold it firmly in position under sufficient tension to keep it taut and secure.

The above object is attained by the structure illustrated in the accompanying drawings, in which:—

Figure 1 is a perspective view of a gate for wire fencing involving my invention, showing said gate in the closed position. Fig. 2 is a perspective view, showing the gate open and supporting itself in a vertical position. Fig. 3 is a perspective view of one of the rings preferably employed in effecting a hinged connection between the sections of the gate. Fig. 4 is a view in horizontal section, showing the position of the parts preparatory to straining the gate longitudinally before fastening it closed. Fig. 5 is a similar view showing the gate locked or secured in the closed position. Fig. 6 is a detail, partly in section, showing the rotatable post journaled at its ends in the cap and base pieces, and provided with projecting pins which engage the end piece of the gate, and by a rotation of said post, strain the gate longitudinally to render it taut

when closed. Fig. 7 is an elevation of one of the end pieces of the gate.

Difficulty has heretofore been encountered in providing a gate of the fence fabric for a light or flexible wire fencing which is not self-sustaining in its character, because of the tendency of such a gate, when open, to lie over on the ground, thereby becoming bent and broken and often destroyed by stock running into it. By means of the gate as shown and described herein, I am able to provide a gate for a flexible wire fencing which is self-sustaining when open, and which may be securely fastened when closed so as to obviate any weakness in the fence at that point.

Referring to the drawings, by the characters of reference marked thereon, 1 designates the post at one side of the gate opening to which the gate is hinged, and to which one terminal of the line fence 2, which is of the woven wire type, is secured.

The gate consists of a plurality of joined sections, and is herein illustrated as composed of two sections, designated as sections 3 and 4. The sections of the gate are of substantially the same material and construction as the fencing and comprise longitudinal strands 5 connected by vertical stays 6. One end of each of the strand wires of section 4 of the gate is provided with a loop or eye 7, through which is passed a fastening wire 8 or other suitable fastening device, to connect the eyes or loops 7 of the strand wires to the post in such a manner as to effect a joint or hinge, as illustrated in Figs. 1 and 2. The sections of the gate are fastened together, so as to effect a jointed connection between them, by providing the terminals of the strand wires with eyes 9, which are joined by the connecting rings 10 that pass through said eyes, as clearly shown in Fig. 3, thereby joining the sections of the gate in such a manner as to enable one section to be folded onto the other, or the gate to be broken in the center and the free end thereof carried toward the hinged end, as illustrated in Fig. 2. By this arrangement, the jointedly connected sections of the gate

may be so disposed relatively, by causing them to stand at an angle to each other when the gate is open, as to afford a brace one for the other, whereby the sections of the gate are held in a vertical position, and notwithstanding the flexible nature thereof, are prevented from bending over and lying

on the ground, a result which would follow were it attempted to form the gate of a single section, and open it by swinging the entire section from the hinge on the post 1.

5 If desired, the gate may be formed in three sections instead of two, and said sections placed in a zigzag form when the gate is open to hold them in an upright position.

10 It will be evident that the free end of the gate may be swung outwardly, and caused to stand from the section hinged to the post at an angle thereto, so as to afford the full area of the gate opening, instead of being disposed as shown in Fig. 2. The only advantage 15 in opening the gate as shown in Fig. 2 is that the free end thereof may be carried directly toward the hinge post 1 instead of being swung in the arc of a large circle, as would be necessary were the gate opened by 20 swinging its free end outwardly.

25 To provide for closing the gate and securing it in the closed position, a main post 11 is employed which is set a suitable distance into the ground, as shown in Fig. 6, and to which the terminal of the line fence is secured, as shown in Figs. 1 and 2. The post 11 passes through a suitable base 12, which rests upon the ground, and upon the upper end of said post is a suitable cap 13. Rigidly secured at its ends in the base and cap respectively, is an auxiliary post 14. Journated at its ends in the base and cap is a rotatable post 15, having projecting from the periphery thereof a vertical row 30 of pins 16. Secured to said rotatable post is a collar 17, provided in its periphery with a plurality of sockets 18, for the insertion of a bar or lever.

35 The free end of the section 3 of the gate is provided with a comparatively rigid end-bar 19, with which the terminals of the strand wires are connected. It will be noted that the posts 11, 14 and 15 are disposed in triangular form. In closing the gate, the free end of the section 3 thereof, is carried to the rotatable post 15, so as to enable the projecting pins 16 thereon to engage the rear face of the end-bar 19 between the strand wires, as shown in Fig. 4, 45 when by inserting a lever 20 in one of the sockets 18 of the collar 17, the post 15 may be rotated to place a longitudinal strain or tension upon the gate to render it taut, as

50 shown in Fig. 5, in which position said parts may be secured by inserting a locking pin 21 into one of the sockets 18 of the collar 17, and allowing said pin to rest against the auxiliary post 14, thereby maintaining the tension upon the gate, and holding it securely locked or closed. The gate may be 55 readily opened by turning the rotatable post 15 sufficiently to free the locking pin 21, when said pin may be withdrawn to allow the post 15 to turn backwardly and permit a disengagement of the end-bar 19 of the 60 gate from the pins 16 thereof, when said gate may be swung to the open position, as described. This arrangement enables the gate to be located at any desired point in the line fence at comparatively little expense, 65 and provides for sustaining the gate, when opened, in a vertical position in a manner to prevent it from injuring itself by falling over onto the ground, and obviating the liability of injury thereto by stock trampling 70 thereon.

Having thus fully set forth my invention, what I claim as new and desire to secure by Letters Patent is:—

1. A gate of flexible wire fabric, comprising a plurality of sections jointedly connected, a post, means for hinging the end of one of said sections to said post, a rotary post having projecting pins adapted to engage the section at the free end of the gate, 85 means for rotating said post to place a longitudinal strain upon the gate, and means for locking the gate under longitudinal tension.

2. A gate composed of flexible wire fabric, 90 and comprising a plurality of sections, the end of one section being hinged to a stationary post, means for connecting the sections together to effect a hinged joint, a rotatable post, a plurality of pins in the said 95 post for engaging the end of the said gate, and means for turning the said post to draw the sections thereof into longitudinal alinement.

In testimony whereof, I sign this specification in the presence of two witnesses.

JOHN WALLACE PAGE.
